Jordan Gathin, Manufacture, &c., North Carolina 8908X

Sutton Patent

The Schedule referred to in Marc Sutton's Patent and making part of the same, containing a description in the words of the said Jordan Gathin, himself of his improvement in the machine for thinning Cotton.

To all to whom these presents shall come. Be it known that Jordan Gathin of Manufacture, in the County of Hertford and State of North Carolina have invented a new and useful improvement in the machine for Thinning Cotton, and that the following is a full and exact description of the construction and operation of the said machine as invented or improved by me. It has been devised for the purpose of facilitating and reducing labour of Thinning Cotton and that the operation of the day-lip may follow immediately after that of Thinning and may be advantageously done in any other. As the Construction an oblong frame is made of convenient width to stand in the row in order that the centre of it may pass over the Cotton plants it may be of about the necessary length of a plough and the two ends of the side pieces are connected by a bar running across from one to the other. At that end intended for the back is to rise an upright Standard at each end of the cross piece through the upper part of which there is a brace for the purpose of sustaining the arms or handles of the frame at their proper distance under and which slope downwards to the frame which they join at the side pieces when at the centre of the length. To the front cross piece is attached a single tree to the horse to draw by. In about the centre of the sides of this frame, or as it is often termed, between the two parallel with the line already described.

On each end of this piece is placed a wheel, one being placed near the side pieces and between the sides and of such a diameter as to raise the frame enough above the plants & on these two wheels the weight of the frame is sustained which causes them to revolve. One (say that on the right hand) is simply a wheel without teeth but the other has a row of pegs standing out from the side towards the centre of the frame or in lines parallel with the axle which work in those of a smaller wheel of smaller dimensions proportioned to the number of revolutions of each of the other desired. This knuckle is turned upon an axis passing through

it having one of its gudgeons revolving in a hole sunk in the crop piece or axle, & the other gudgeon in another hole formed in the frame at the front end and it is situated in the same side of the frame and parallel with the sides. The revolution of the large wheel carry round this timble with them (it being fast on the axis) and between the end of it, and the two crop pieces in front, is to cause in the axis a wooden block through which is passed an iron arm or hook and through it, projecting sufficiently from either side to reach the Cotton plants at the their roots. Crop these arms at their ends, and cause this piece of iron to stick to act as a hook or cutter so to be of such a strength as is desirable to thin out the plants & each one of these arms will then form a hook & if necessary another pair may be passed at right angles with these more or one hook only being used as may be thought best. This axis with its timbered end hook may be placed either in front of the centre crop piece, or behind, as will best suit, and in order to side up the Cotton after the hoes there is to be placed behind these and descending from the bottom of the side pieces a Cultivator & a horse-hoe, or other tool for the purpose to hedge up the ground on one or both sides of a row.

Should the plants be in some places too thin so that it will be desirable to thin them out at occasional distances only then the Cultivator and Cultivator tool may be dispensed with by which means the hoes are placed more at command so that by simply raising either the end or the other of the frame, by the handles according as they are placed either before or behind the centre crop pieces they can be brought into action where the plants may stand thickest, and interfere in a given area, as pleasure...

What I claim as my invention, and not before known in the above described machine, is the machinery in which I have combined the operation of the wheels & hoes, in the interior of the frame so as to produce the application I have described of giving motion to the said hoes. The testimony that the above is a full, clear & exact description of the construction and mode of operation of my machine as invented by me I have hereunto set my hand the twenty fifth day of May eighteen hundred and thirty six
